(57) **CLAIM**

The ornamental design for a diaper changing frame with cloth sling, as shown and described.

DESCRIPTION

FIG. 1 is a diaper changing sling showing our new design therefor, the parts in phantom line forming no part of the design and the parts in dotted line representing stitching; FIG. 2 is a side elevational view, the opposite side being identical;

FIG. 3 is an end view thereof, the opposite end being identical;

FIG. 4 is a top plan view thereof; and,

FIG. 5 is a bottom plan view thereof.
